UNITED STATES PATENT OFFICE.

RALPH ERNEST GIBSON AND HERBERT NICOLL, OF LIVERPOOL, ENGLAND.

DISCHARGE CHUTE.

1,424,010.

Specification of Letters Patent. Patented July 25, 1922.

Application filed May 13, 1922. Serial No. 560,691.

To all whom it may concern:

Be it known that we, RALPH ERNEST GIBSON, and HERBERT NICOLL, subjects of the King of Great Britain, both residing in Liverpool, in the county of Lancaster and Kingdom of England, have invented certain new and useful Improvements in Discharge Chutes, of which the following is a specification.

10 This invention has for its object to provide means whereby red-hot coke pushed out of gas-retorts, coke-ovens or similar apparatus, by means of discharging machines, may be delivered to a quenching-bench or 15 other cooling apparatus, fixed outside the retort-house or in other convenient position, in an unbroken condition and as expeditiously as possible, or even into producers. The object is achieved according to this 20 invention by means of a tube, or tubes, preferably lined with fire-clay, through which the red-hot coke passes from the retort to the cooling apparatus, (or to outside producers) and hinged so as to have a radial 25 movement, curved tubular bridge-pieces being provided for connecting the tube (or tubes) to the upper tiers of retorts. The tube and bridge-pieces are mounted on a travelling carriage to enable the tube to be 30 moved along in front of the retorts and means are provided for adjusting the tube (or tubes) to any required position.

When the coke is handled by these means the work is more economically, expeditiously, and better done than hitherto, the coke is of better quality, and the retort-house is kept as free as possible from heat, dust and fumes, with consequent greater comfort to the workmen.

40 The invention will be understood from the following description, reference being had to the accompanying drawings in which:

Figure 1 is a section through the discharging stage of a retort-house, showing our apparatus in side elevation adapted to work in conjunction with five tiers of horizontal retorts.

Figure 2 is a front elevation of the apparatus.

50 Referring to the drawings, 1 denotes the tube, which is preferably made in cross section to suit the shape of the retort from which the coke is discharged, and of a convenient length to suit the width of the discharging stage. The tube is preferably lined with fire clay slabs bolted to a metal

casing in such a manner as to allow for expansion and contraction.

The tube 1 is hinged or pivoted at its delivery end at 2, so as to be capable of being raised radially by hoisting means from the approximately horizontal position (illustrated by broken lines) in which it receives coke from the lowest tier of retorts 3 to the inclined position (shown in full lines) for receiving coke from the uppermost tier of retorts.

The gap between the upper tiers of retorts 3 and the tube 1 due to the radial movement of the latter is bridged over by curved tubular bridge-pieces 4 of varying length and of a cross section similar to that of the tube. These bridge-pieces are constructed and positioned in such a manner that the top of such bridge-pieces will deflect the coke from its horizontal travel to the angle of the tube, and an unbroken path is always maintained between the retort and the point of delivery, the bridge pieces 4 being curved to such a radius that the coke passes down the tube in the same condition as it leaves the retort. The bridge-pieces 5 for the lower retorts may not be of tubular form, but flat or slightly curved, and set horizontally or at a slight inclination as required.

The tube 1, the bridge pieces 4 and 5 and the operating gear hereinafter described are mounted in a carriage 6, comprising a platform and a framework superstructure of any suitable construction. This carriage is adapted to travel by wheels 7 on rails 8 laid on the discharging stage 9 of the retort-house.

On the tube 1 is fixed a hoisting bridle 10, to which is connected a hoisting rope or chain 11 which passes over pulleys 12 at the top of the travelling carriage and thence downwards to a hoisting drum or the like 13.

The apparatus as described is operated by a reversible electric motor 14, supplied with current through a power-collecting arm 15 and is provided with spur-wheel reducing gear 16, 17 is the controller for the motor, 18 is the driver's platform. The machine 105 could however, if desired, be operated by hand.

The hoisting drum 13 is driven from the motor by worm wheel reduction gear 19. 20 is a clutch for controlling the operation 110 of the hoisting drum.

The travelling wheels 7 of the machine are

driven through worm wheel reducing gear 21 and mitre-wheels 22, and the travelling gear is thrown into or out of operation by a clutch 23 which together with the clutch 5 for hoisting drum is controlled by a hand-lever 24 mounted on the driver's platform.

The mode of operation of the apparatus is as follows:—

When receiving the coke from the bottom 10 tier of retorts 3, the tube 1 is held in an approximately horizontal position, (as shown in broken lines in Fig. 1) forming what is practically an extension of the retort 15 and connecting thereto as near as practicable. The coke is then pushed by the discharging machine direct into the tube in the natural form, a portion being delivered direct to the cooling apparatus in cases where the tube is shorter than the retort and the 20 tube is then inclined on its hinge 2 to an angle sufficient to deliver the remainder of the coke by gravity to the quenching-table 25.

When receiving coke from retorts at a 25 higher level than the point of delivery, the receiving end of the tube is inclined to a suitable angle by operating the hoisting gear and the gap between the retort and the tube due to the radial movement of the tube 30 is bridged over by one of the curved bridge-pieces 4 in such a manner that an unbroken path is always maintained between the retort and the point of delivery, and the coke 35 is deflected from its horizontal path and passes down the tube in the same condition as it leaves the retort.

The space between the delivery end of the tube and the inclined quenching-table 25 is bridged by the hinged apron-plate 26, 27 40 is a vertically sliding door for closing the opening in the wall of the retort-house if desired and is fitted with balance-weights 28.

In thus describing the invention, we do 45 not limit ourselves to the particular details described, as modifications in various parts of the apparatus, such as in the operating mechanism and in the construction of the hinged tube, bridge-pieces and travelling 50 carriages may be made without departing from the scope of the invention.

We declare that what we claim is:—

1. A discharge chute mechanism for furnaces of the type having carbonizing chambers arranged in superposed tiers, comprising 55 in combination, a carriage arranged to travel along the furnace front; a plurality of superposed tubular guides mounted on said carriage in position to register with successive tiers of said chambers; and a tube 60 movably mounted on said carriage so as to be capable of registering selectively with said tubular guides.

2. A discharge chute mechanism for furnaces of the type having carbonizing chambers arranged in superposed tiers, comprising 65 in combination, a carriage arranged to travel along the furnace front; a plurality of superposed curved tubular guides so mounted on said carriage that one end of each guide will register with chambers of a corresponding tier, the opposite ends of the guides terminating substantially on an arc of a circle; and a tube hinged to said carriage substantially at the center of said circle 75 and capable of swinging into register selectively with said tubular guides.

3. A discharge chute mechanism for furnaces of the type having carbonizing chambers arranged in superposed tiers, comprising 80 in combination, a carriage arranged to travel along the furnace front; a plurality of superposed tubular guides mounted on said carriage in position to register with successive tiers of said chambers except the 85 lowest; and a tube movably mounted on said carriage so as to be capable of registering selectively with any of said tubular guides and with retorts of the lowest tier.

4. A discharge chute mechanism for furnaces of the type having carbonizing chambers arranged in superposed tiers, comprising 90 in combination, a traveling carriage; a plurality of curved bridging guide tubes varying in length and mounted in said carriage so as to register with upper tiers of retorts; a discharge tube conforming in cross-section with said retorts and with said bridging guide tubes, said discharge tube being pivoted at its delivery end to said 100 carriage and being capable of swinging into register with any of said bridging tubes; and hoisting means for raising and lowering the receiving end of said tube.

5. A discharge chute mechanism for furnaces of the type having carbonizing chambers arranged in superposed tiers, comprising 105 in combination, a travelling carriage; curved bridging tubes mounted in said carriage; a discharge tube hinged at its delivery end to said carriage and capable of swinging into register with said bridging tubes selectively; hoisting means for raising and lowering said discharge tube; an electric motor on said carriage; and driving 110 connections whereby said motor may propel said carriage or operate said hoisting means selectively.

In witness whereof, we have hereunto signed our names this 1st day of May 1922, 120 in the presence of two subscribing witnesses.

RALPH ERNEST GIBSON.
HERBERT NICOLL.
